RADIOTHERAPY IRRADIATION UNIT

Peter Waine, Stockport, England, assignor to Fairey Engineering Limited, Heston, Middlesex, England, a company of Great Britain

Filed May 31, 1966, Ser. No. 2,999

Claims priority, application Great Britain Dec. 1, 1965

Term of patent 14 years

(Cl. D83—1)

FIGURE 1 is a perspective view of a radiotherapy irradiation unit showing my new design;

FIGURE 2 is a side elevation of the opposite side of the unit shown in FIGURE 1; and

FIGURE 3 is a front elevation thereof.

I claim:

The ornamental design for a radiotherapy irradiation unit, as shown.
